DISPENSING CLOSURE FOR A LIQUID CONTAINER

John R. Albert, 8425 Cherokee Lane, Leawood, Kans. 66206, and Asa Pickinpaugh, Kansas City, and Michael A. Waters, Independence, Mo.; said Pickinpaugh and said Waters assignors to said Albert

Filed Feb. 8, 1967, Ser. No. 5,728

Term of patent 14 years

(Cl. D58—26)

Fig.1.

Fig.3.

Fig.2.

Fig.4.

Fig.5.

Fig.6.

FIG. 1 is a front elevational view of a dispensing closure for a liquid container showing our new design;

FIG. 2 is a side elevational view thereof;

FIG. 3 is a rear elevational view thereof;

FIG. 4 is a top plan view thereof;

FIG. 5 is a reduced scale perspective view of a dispensing closure for a liquid container showing another form of our new design; and

FIG. 6 is a slightly enlarged scale top plan view thereof.

We claim:

The ornamental design for a dispensing closure for a liquid container, as shown and described.
